ANTISEPTIC SOAP COMPOSITION

Eugene W. Elliott, Pine Lawn, and Roland S. Shumard, Brentwood, Mo., assignors to Monsanto Chemical Company, St. Louis, Mo., a corporation of Delaware

No Drawing. Application January 22, 1951,
Serial No. 207,246

11 Claims. (Cl. 252—107)

This invention relates to new and novel detergent compositions. More particularly it relates to antiseptic detergent compositions containing a synergistic mixture of a tetra-alkyl thiuram disulfide and a halogenated 2-hydrocarbon substituted-8-hydroxy quinoline or a metal salt thereof. Still more particularly it relates to antiseptic detergent compositions containing a synergistic mixture of tetra-methyl thiuram disulfide and a halogenated 2-methyl-8-hydroxy quinoline more commonly known as halogenated 8-hydroxy quinaldines.

5 tions containing the new mixture are not irritating to the skin.

As exemplary of this invention detergent containing compositions are prepared by intimately mixing the ingredients listed below to form a composite containing 2% by weight "active ingredient":

Composition	A	B	C	D	E
"Ivory" brand neutral white high grade tallow toilet soap..... parts by weight	98	98	98	98	98
Tetra-methyl thiuram disulfide..... do.....	2	1	1	1	—
5,7-dibromo-8-hydroxy quinaldine..... do.....	—	2	1	—	—
5,7-dibromo-8-hydroxy quinoline..... do.....	—	—	1	2	—

15 20 Aliquots of each of the above described compositions containing 2% by weight "active ingredient" are added to a nutrient agar medium so as to give in each instance a concentration of 0.67 p. p. m. of "active ingredient." The agar in each case is then poured into a petri dish, allowed to harden and then is streaked with a 24 hour old culture of *Staphylococcus aureus* of standard resistance. The incubation in each case is made at 37° C. and the period or time of incubation and the degree of growth is noted below:

Table I

Composition	A	B	C	A	B	O	A	C	D	E
Period of Incubation (hrs.)	48	48	48	72	72	72	96	96	96	96
Growth	+	+	—	+++	+++	+	+++	+	+++	+++

Legend:

- No growth.
- ½+ Extremely light growth.
- ++ Very light growth.
- +++ Light to moderate growth.
- ++++ Normal heavy growth.

In co-pending application Serial Number 206,123, filed January 15, 1951, in the name of R. S. Shumard there is described a class of hydroxy substituted aromatic compounds and their alkali metal salts which when incorporated in alkaline media such as soap form highly effective antiseptic detergent compositions. This class of compounds is represented by the formula

where X is a halogen atom, where n is a whole number from 1 to 2, where R is selected from the group consisting of hydrogen, halogen atoms and alkyl groups, where Z is hydrogen or an alkali metal such as sodium, potassium or lithium, and where R' is a hydrocarbon group such as an alkyl, aralkyl, aryl, or an alkaryl group.

In accordance with this invention it has been found that a synergistic antiseptic effect is obtained by employing a halogenated 2-hydrocarbon substituted-8-hydroxy quinoline or an alkali metal salt thereof of co-pending application Serial Number 206,123, filed January 15, 1951, in the name of R. S. Shumard in conjunction with a tetra-alkyl thiuram disulfide in a detergent composition. In other words the resultant antiseptic detergent composition is more active than a detergent composition containing either component and beyond the mere additive effect of the proportions of the individual components. The tetra-alkyl thiuram disulfide and the halogenated 2-hydrocarbon substituted-8-hydroxy quinoline or its alkali metal salt are readily incorporated either separately or admixed with one another in detergent compositions whether the latter be solid or liquid. The components of the new mixture remain permanently in the detergent composition. They do not affect the lathering, cleansing or physical properties of the detergent nor do they impart an unpleasant odor nor discolor the finished detergent composition. Furthermore detergent composi-

40 45 As further exemplary of this invention a halogenated 2-hydrocarbon substituted-8-hydroxy quinoline is added mixed with a tetra-alkyl thiuram disulfide and compounded in a detergent composition to form a 2% by weight "active ingredient" composite and compared to detergent compositions containing an equal weight of each of the respective components.

The compositions are:

Composition	F	G	H
"Ivory" brand neutral white high grade tallow toilet soap.....	98	98	98
Tetra-methyl thiuram disulfide.....	2	1	—
5,7-dichloro-8-hydroxy quinaldine.....	—	2	1

55 60 Aliquots of each of the above described compositions are added to a nutrient agar medium so as to give in each instance concentrations of 0.67 p. p. m. of "active ingredient." The agar in each case is then poured into a petri dish, allowed to harden, and then is streaked with a 24 hour old culture of *Staphylococcus aureus* of standard resistance. In a similar manner aliquots of the afore-described F, G and H compositions containing 2% by weight "active ingredient" are added to a nutrient agar medium so as to give in each instance a concentration of 2.5 p. p. m. of "active ingredient." The agar in each case is then poured into a petri dish, allowed to harden, and then is streaked with a 24 hour old culture of *Salmonella typhosa* of standard resistance. The degree of growth of both *Staphylococcus aureus* and *Salmonella typhosa* is noted below after an incubation period of 72 hours at 37° C. in the respective instances:

Table II

Composition	F	G	H
Organism:			
<i>Staphylococcus aureus</i>	++	+	½+
<i>Salmonella typhosa</i>	+++	+++	+

75 Legend: Same as in Table I.

80 It will be appreciated that the difference between the results obtained with the 2% tetra-methyl thiuram disul-

fide detergent composition (composition F) in this example and the corresponding results in the prior example (composition A) is due to the fact that the test organism (*Staphylococcus aureus*) in each instance was prepared on different occasions. Divergencies of this kind are common in antiseptic technology, however, the respective results for the 2% tetra-methyl thiuram disulfide detergent composition provide proper comparison in each example.

Substantially the same synergistic antiseptic results are obtained with tetra-methyl thiuram disulfide as in the aforescribed examples by replacing the respective 5,7-dihalo-8-hydroxy quinaldines of compositions C and H with other dihalogenated-8-hydroxy quinaldines such as 5,7-diodo-8-hydroxy quinaldine, 5-chloro-7-iodo-8-hydroxy quinaldine, and 5-chloro-7-bromo-8-hydroxy quinaldine. A synergistic antiseptic effect is also obtained with a detergent composition containing a minor proportion of equal parts by weight of tetra-methyl thiuram disulfide and 5-chloro-8-hydroxy quinaldine.

While combinations of tetra-methyl thiuram disulfide and a mono- or di-halogenated-8-hydroxy quinaldine, particularly the 5,7-dihalo-8-hydroxy quinaldines of the formula

where X_1 and X_2 are like or unlike halogen atoms, are the most effective and exhibit the most pronounced synergistic antiseptic effect when admixed in a detergent composition, other halogenated 2-hydrocarbon substituted-8-hydroxy quinaldines and their alkali metal salts when admixed with tetra-methyl thiuram disulfide in a detergent composition also exhibit synergism. As exemplary of such are:

5-bromo-8-hydroxy quinaldine
5-iodo-8-hydroxy quinaldine
6-chloro-8-hydroxy quinaldine
7-chloro-8-hydroxy quinaldine
7-bromo-8-hydroxy quinaldine
7-iodo-8-hydroxy quinaldine
5-bromo-7-methyl-8-hydroxy quinaldine
5-bromo-7-tert. butyl-8-hydroxy quinaldine
5,6,7-tri chloro-8-hydroxy quinaldine
5,6,7-tri bromo-8-hydroxy quinaldine
2-ethyl-5-chloro-8-hydroxy quinaldine
2-ethyl-5,6-dichloro-8-hydroxy quinaldine
2-propyl-5,7-dichloro-8-hydroxy quinaldine
2-butyl-5,7-dichloro-8-hydroxy quinaldine
2-phenyl-5-bromo-8-hydroxy quinaldine
2-phenyl-5,7-dibromo-8-hydroxy quinaldine
2-benzyl-5,7-dibromo-8-hydroxy quinaldine

The alkali metal salts of the aforementioned hydroxy substituted compounds of this invention when combined with a tetra-alkyl thiuram disulfide, such as tetra-methyl thiuram disulfide, in a detergent composition also exhibit a synergistic antiseptic effect, however, the alkali metal salts are not as effective as the parent compound.

Of the tetra-alkyl thiuram disulfides tetra-methyl thiuram disulfide is preferred, however, other tetra-alkyl thiuram disulfides such as the tetra-ethyl and the tetra-butyl thiuram disulfide when employed in conjunction with a halogenated 2-hydrocarbon substituted-8-hydroxy quinaldine exhibit an antiseptic synergistic effect in a detergent composition.

Relatively small amounts of the synergistic mixture of a tetra-alkyl thiuram disulfide and a halogenated 2-hydrocarbon substituted-8-hydroxy quinaldine in a detergent composition yield effective antiseptic detergent compositions. Amounts as low as 0.5-1% by weight of the mixture based upon the weight of the detergent have proved satisfactory in some instances. However, it is preferred to employ amounts in the order of 1-3% by weight. Larger amounts may be employed, as for example up to 10% by weight of the synergistic mixture, however, the upper limit used is determined by practical considerations.

The proportions of the component parts of the synergistic mixture will vary between wide limits depending upon the particular tetra-alkyl thiuram disulfide and halogenated 2-hydrocarbon substituted-8-hydroxy quinaldine.

employed, the availability and cost of the component parts, the detergent base, and the purpose of the antiseptic detergent composition. However, in general the weight ratio of the tetra-alkyl thiuram disulfide to the halogenated 2-hydrocarbon substituted-8-hydroxy quinaldine or its alkali metal salt will vary from 25-75 parts of the former to 75-25 parts of the latter. While particularly good synergistic antiseptic results are obtained employing a weight ratio of 40-60 parts of a tetra-alkyl thiuram disulfide to 60-40 parts of a halogenated 2-hydrocarbon substituted-8-hydroxy quinaldine or its alkali metal salt the preferred mixture is that containing equal weights of each component.

Other antiseptic agents may be incorporated in the new antiseptic detergent composition as well as emollients, water softeners and the well known "vehicles" of the detergent trade. Various colors, antioxidants, perfumes and the like may be incorporated where desirable.

The term "detergent" includes soap and synthetic detergents, particularly the anionic detergents such as the substituted amides and the alkyl aryl sulfonates. The term "detergent" includes also mixtures of synthetic detergents and soap. The term "soap" or "detergent soap" as used herein is employed in its popular or ordinary meaning, that is, those cleansing compositions prepared from an alkali metal compound such as sodium or potassium hydroxide and a fat or fatty acid.

The halogenated 2-hydrocarbon substituted-8-hydroxy quinaldines or their metal salts and the tetra-alkyl thiuram disulfides of this invention may be added to the detergent composition in any suitable manner during the crutching or milling or similar operation. The halogenated 2-hydrocarbon substituted-8-hydroxy quinaldines or their metal salts and the tetra-alkyl disulfide may be first dissolved either separately or jointly in a suitable solvent and then incorporated in the detergent if so desired. In general any method which results in the halogenated 2-hydrocarbon substituted-8-hydroxy quinaldines or their alkali metal salts and the tetra-alkyl thiuram disulfides of this invention being uniformly incorporated in the final detergent composition is satisfactory.

While the invention has been described relative to several particular embodiments it is to be understood it is not so limited but that many variations and modifications which are obvious to those skilled in the art to which the invention appertains may be made without departing from the spirit or scope of the invention.

What is claimed is:

1. An antiseptic detergent composition comprising a detergent soap and a minor weight proportion in respect to the detergent soap sufficient to impart antiseptic properties of a mixture of a halogenated 2-hydrocarbon substituted-8-hydroxy quinaldine of the formula

where X is a halogen atom, where n is a whole number from 1 to 2, where R is selected from the group consisting of hydrogen, halogen atoms and short-chain alkyl groups, and where R' is a hydrocarbon group containing not more than 7 carbon atoms selected from the group consisting of alkyl, aralkyl, aryl and alkaryl radicals, and a tetra-alkyl thiuram disulfide wherein each alkyl substituent is a short-chain alkyl group, said thiuram disulfide being a synergist for said halogenated compound.

2. An antiseptic detergent composition comprising a detergent soap and a minor weight proportion in respect to the detergent soap sufficient to impart antiseptic properties of a mixture of tetra-methyl thiuram disulfide and a halogenated 8-hydroxy quinaldine of the formula

where X is a halogen atom and where n is a whole number from 1 to 2, the proportions of the components of said mixture being 25-75 parts by weight tetra-methyl thiuram disulfide to 75-25 parts by weight halogenated 8-hydroxy quinaldine.

3. An antiseptic detergent composition comprising a detergent soap and a minor weight proportion in respect to the detergent soap sufficient to impart antiseptic properties of a mixture of tetra-methyl thiuram disulfide and a di-halo-8-hydroxy quinaldine of the formula

where X_1 and X_2 are halogen atoms, the proportions of the components of said mixture being 40-60 parts by weight tetra-methyl thiuram disulfide to 60-40 parts by weight di-halo-8-hydroxy quinaldine.

4. An antiseptic detergent composition comprising a detergent soap and a minor weight proportion in respect to the detergent soap sufficient to impart antiseptic properties of a mixture of equal parts by weight of tetra-methyl thiuram disulfide and a di-halo-8-hydroxy quinaldine of the formula

where X_1 and X_2 are halogen atoms.

5. An antiseptic detergent composition comprising a detergent soap and 0.5 to 10% by weight based-upon the detergent soap of a mixture of equal parts by weight of tetra-methyl thiuram disulfide and a dihalo-8-hydroxy quinaldine of the formula

where X_1 and X_2 are halogen atoms.

6. An antiseptic detergent composition comprising a detergent soap and 1 to 3% by weight based upon the detergent soap of a mixture of equal parts by weight of

tetra-methyl thiuram disulfide and a di-halo-8-hydroxy quinaldine of the formula

where X_1 and X_2 are halogen atoms.

7. An antiseptic detergent composition comprising a detergent soap and 1 to 3% by weight based upon the detergent soap of a mixture of equal parts by weight of 5,7 - dichloro - 8-hydroxy quinaldine and tetra-methyl thiuram disulfide.

8. An antiseptic detergent composition comprising a detergent soap and 1 to 3% by weight based upon the detergent soap of a mixture of equal parts by weight of 5,7 - dibromo-8-hydroxy quinaldine and tetra-methyl thiuram disulfide.

9. An antiseptic detergent composition comprising a detergent soap and 1 to 3% by weight based upon the detergent soap of a mixture of equal parts by weight of 5-chloro-7-bromo-8-hydroxy quinaldine and tetra-methyl thiuram disulfide.

10. An antiseptic detergent composition comprising a detergent soap and 1 to 3% by weight based upon the detergent soap of a mixture of equal parts by weight of 5-chloro-7-iodo-8-hydroxy quinaldine and tetra-methyl thiuram disulfide.

11. An antiseptic detergent composition comprising a detergent soap and 1 to 3% by weight based upon the detergent soap of a mixture of equal parts by weight of 5-chloro-8-hydroxy quinaldine and tetra-methyl thiuram disulfide.
